his ATTORNEY

UNITED STATES PATENT OFFICE

THEODORE H. WITTLIFF, OF CLEVELAND, OHIO

FURNITURE BRACE

Application filed December 16, 1929. Serial No. 414,353.

The present invention relates to furniture braces and an object thereof is to provide a construction having stronger bracing qualities. Another object of the invention is to provide a construction in which two spaced strands lead substantially in parallel relation to the bracing points on the furniture. Still another object is to form from a single strip of material two strands so connected to the furniture that they act as a unit while at the same time giving better bracing qualities than a single strand. A further object of the invention is to provide a novel tightening means designed for parallel tightening strands. Another and further object is to provide an improved anchoring device designed for use at a corner of furniture. Still another and further object is to provide an anchoring device for two tightening strands formed from a single strip of material.

To these and other ends, the invention consists of certain parts and combinations of parts all of which will be hereinafter described: the novel features being pointed out in the appended claims.

In the drawing:

Fig. 1 is a horizontal sectional view through the legs of a chair equipped with one embodiment of the present invention;

Fig. 2 is a section on the line 2—2, Fig. 1;

Fig. 3 is a detail view partially in section of a tightening means embodying this invention on the line 3—3, Fig. 1;

Fig. 4 is a perspective view of one of the two strand anchoring devices;

Fig. 5 is a perspective plan view of the other two strand anchoring devices;

Fig. 6 is a sectional view showing an anchoring device similar to that illustrated in Fig. 4 designed for a single strand; and

Fig. 7 is a perspective view of the anchoring device illustrated in Fig. 6.

In the embodiment illustrated in Fig. 1, the furniture is in the form of a chair having its four legs 1 each provided with two transverse diagonally extending bores 2 arranged parallel.

The tightening strands 3 are four in number and are arranged in pairs, the members of each pair being substantially parallel and

being formed from a single strip of material bent between its ends to provide the two strands and the connecting portion or bend 4. Each pair of strands connects two legs on one side of the furniture and has its portions near the bend 4 lying in two bores in one leg and its portions near its other ends lying in the two bores of the other leg on the same side of the furniture.

For anchoring the strands to the leg adjacent the bend there may be provided an anchoring member formed, in this instance, from sheet material bent to provide two meeting surfaces 5 at angles to each other for cooperation with two angularly arranged faces on a leg. This plate is perforated at 6 for the passage of two strands and is pressed inwardly at 7 between the openings or perforations 6 to provide a groove in which the bend 4 lies.

For anchoring the other ends of the strands, an anchoring member may be provided comprising a head having two angularly arranged surfaces 8 from the meeting line of which two bodies 9 project, one above the other. These bodies are preferably externally tapered to their free ends, and having bores 10 which flare toward the outside of the head so as to be larger at their outer than their inner ends. The strands pass through these bodies 9 and are kinked or bent at 11 at their ends, the bent portions lying in the enlarged ends of the bores 10. The angularly arranged faces on the head serve to hold the anchoring member against turning and also to protect the corner of the furniture.

The tightening means for the strands may comprise a tension rod 12 having external threads 13 at one end and strand engaging means at the other end projecting from opposite sides of the longitudinal axis of the rod and formed with strand receiving grooves 14 on opposite sides of the axis to slidably engage with two strands on one side of the furniture. Adjustably mounted on the tension rod 12 for adjustment toward and from the rigid strand engaging means is a strand engaging means 15 in the form of a block having two grooves 16 lying on opposite sides

of the longitudinal axis of the rod 12 for receiving the two strands connected with the other side of the furniture. A nut 16^a is adjustable on the screw threaded portion 13 of the rod 12 and serves to effect relative adjustment between the strand engaging portion of the tightening device. The strand engaging member 15 is also rotatable on the tension bolt or rod 12, thus permitting the tension device to adapt itself to inequalities in the strands on the two sides of the furniture.

A modification of the invention is shown in Figs. 6 and 7 and is designed for a single strand arrangement. The single strand 3^a is secured at opposite ends to two anchoring devices each of which has two meeting surfaces 8^a from the line of joinder of which projects a single body 9^a which has a flaring bore or opening 10^a in which the end of the strand 3^a is secured. Any suitable form of tightening device may be used with this form of the invention.

What I claim as my invention and desire to secure by Letters Patent is:

1. An anchoring device for furniture braces comprising a body having an opening extending therethrough for the passage of a tightening strand, said opening being larger at its outer than its inner end to permit the anchorage of a tightening strand end therein and being provided adjacent its outer end with an abutment head having angularly arranged faces for cooperating with two angularly arranged side faces of a leg.

2. An anchoring device for furniture braces comprising two bodies, each having an opening extending therethrough for the passage of a tightening strand, each opening being larger at its outer than its inner end to permit the anchorage of the end of a tightening strand therein, and a head connecting said two bodies, and having angularly arranged surfaces for cooperating with the furniture into which the bodies project.

3. In combination with an article of furniture having two pairs of bores, two tightening strands formed from a single strip of material bent between its ends, the portions of the strip adjacent the bend lying in two of the bores with the bend extending between the bores, and the portions of the strip adjacent the ends of such strip lying in the other two bores, and an anchoring member having two openings and a groove extending between the openings, the groove receiving the bend in the strip between the two strands and the openings having the strands leading from the bend passing therethrough, said anchoring member having two angularly arranged abutment surfaces lying on opposite sides of and parallel with the groove.

4. An anchoring member for furniture braces comprising a body having two meeting, angularly arranged, surfaces for coop-

erating with two angularly arranged faces on the furniture, said body having two openings at the junction of the angularly arranged surfaces for the passage of two tightening strands, and also having a groove in its outer face connecting the two openings for receiving a connection between such two tightening strands.

5. An anchoring member for furniture braces comprising a body having two meeting angularly arranged surfaces for cooperating with two angularly arranged faces on the furniture, said body having two openings at the junction of the angularly arranged surfaces for the passage of two tightening strands.
